Primary Examiner — Calvin E Vansant*Assistant Examiner* — Giang Hoang Tran(74) *Attorney, Agent, or Firm* — J. Wiley Horton(57) **CLAIM**

The ornamental design for an “auto stereo mounting device,” as shown and described.

DESCRIPTION

FIG. 1 is a perspective view of an auto stereo mounting device having two parts that fit together, showing my design; FIG. 2 is a rear perspective view of FIG. 1; FIG. 3 is a front elevation view of FIG. 1; FIG. 4 is a rear elevation view of FIG. 1; FIG. 5 is a left side elevation view of FIG. 1; FIG. 6 is a right side elevation view of FIG. 1; FIG. 7 is a top plan view of FIG. 1, showing the two parts together; and, FIG. 8 is a bottom plan view of FIG. 1, showing the two parts together. The broken lines shown in all views illustrate mounting features which form no part of the claimed design.

1 Claim, 8 Drawing Sheets(56)
